UNITED STATES PATENT OFFICE.

WILLIAM H. LE SUER AND FRED R. BASSETT, OF PAW PAW, MICHIGAN.

MEANS FOR OPERATING CHURNS.

SPECIFICATION forming part of Letters Patent No. 660,516, dated October 23, 1900.

Application filed April 2, 1900. Serial No. 11,223. (No model.)

To all whom it may concern:

Be it known that we, WILLIAM H. LE SUER and FRED R. BASSETT, citizens of the United States, residing at Paw Paw, in the county of 5 Van Buren and State of Michigan, have invented a new and useful Means for Operating Churns, of which the following is a specification.

Our invention relates to improvements in 10 motors, and more particularly to improvements in hand-motors which are adapted for use in actuating revolving barrel or box churning, although the motor itself is adapted for use in various connections not necessary 15 to enumerate here.

One object of our invention is to provide a motor of the class described in which the power is delivered to a crank effectively in all 20 positions.

It is also an object to provide a simple and 25 efficient motor which can be manufactured at a reasonable cost for use as a light motor generally.

Further objects will appear in the detailed 30 description to follow.

We accomplish the objects of our invention by the devices and means described in this 35 specification.

The invention is clearly defined and pointed 40 out in the claim.

A structure or mechanism embodying the 45 features of our invention as applied to a churn is clearly illustrated in the accompanying drawings, forming a part of this specification, in which—

Figure 1 is a side elevation of a hand-operating lever-toggle and connections constituting the main parts of our improved motor, no supporting-framework being illustrated. Fig. 40 2 is a side elevation of our motor applied to a revolving barrel or box churn. Fig. 3 is a front elevation of the structure appearing in Fig. 2, illustrating the relation of the parts.

In the drawings similar letters of reference 45 refer to similar parts throughout the several views.

Referring to the lettered parts of the drawings, A A are suitable standards at each side, carried on a suitable base, the base in this instance being made up of side pieces B B, connected together by braces or rods C C C. The upper ends of these standards A are provided

with bearings for the trunnions E F on the side of the barrel D, the trunnion F being provided with a crank F', which is either 55 formed integral or suitably attached thereto. A lever G is pivoted to the base at H and is arranged vertically and extends to a convenient height for operating the motor. A toggle made up of links M N is connected to the 60 handle of the crank F' at one end and to the pivot O on the base or frame at the opposite end. Connected to the arms or links of this toggle, intermediate to their ends, are shorter links K K, the same being pivoted thereto at 65 d and pivoted to each other at L, these parts forming sides of a quadrangle the opposite sides of which are preferably equal. A pitman I has a pivotal connection at J to the lever G and is also secured to the pivot L between the links K K. As these parts last 70 enumerated are all pivotally connected together, it will be observed that by moving the lever back and forth the motion of the same will be imparted through the pitman I to the 75 toggle M N by the connecting-links K K.

This motor is especially well adapted for use as a churn-motor on account of the perfect control which the operator has of the barrel or box of the churn, it being desirable to 80 rotate the churn comparatively slowly in order that the contents of the churn may move freely within, a too-rapid motion having the effect of causing centrifugal action, which in a measure prevents any motion of the cream 85 at all. The motor, however, is especially practical for any light work, and there are many uses to which it can be applied, which we will not here attempt to enumerate, as we desire to particularly claim the motor in connection 90 with a barrel-churn at this time, drawing a specific claim to that combination. We desire to remark in this connection that a lever or other connection can be made to a toggle direct without any intervening links K K; but 95 that structure would not be so effective as the structure embracing the links K K, which secure an additional advantage.

Having thus described our invention, what we claim as new, and desire to secure by Letters Patent, is—

The combination of a suitable base with standards A, A, to each side thereof; a barrel or box with trunnions resting in suitable

bearings on said standards, one of the said trunnions being provided with a crank; a toggle consisting of links M, N, one end of which is connected to said crank, and the opposite end pivoted to the frame; an actuating-lever G; a pitman therefrom; and links K, K, connecting the end of the pitman pivotally to the links M, N, of the toggle, all coacting sub-stantially as described, for the purpose specified.

WILLIAM H. LE SUER.
FRED R. BASSETT.
